ADJUSTABLE NOZZLE

Filed July 28, 1932

INVENTOR.
Gerald H. Diederich

BY *Alvin C. Brown.*

ATTORNEY.

General description of my invention is as follows: A nozzle assembly for discharging liquid or other materials, such as water, from a hose, having a shank 10, having one end threadedly engaging the nipple end 11 of a shut-off valve 12, and having an externally threaded opposite end 13 for engaging a forty-five degree elbow 14, although obviously the elbow could comprise an integral part of the shank. Threadedly engaging or otherwise secured in the end of the elbow opposite the shank is a socket member 15, preferably counterbored to produce

UNITED STATES PATENT OFFICE

1,923,425

ADJUSTABLE NOZZLE

Gerald H. Diederich, Kansas City, Kans.

Application July 28, 1932. Serial No. 625,372

5 Claims. (Cl. 299—111)

My invention relates to nozzles and more particularly to a device of that character adapted especially for use on fire hose or the like.

With present equipment available for fighting fires it is extremely difficult to reach comparatively small fires as for example those located within walls, between floors, in closed automobiles, around bins and chutes, etc. Not only does such equipment necessitate a frequent interchange of straight and bent nozzles and change of position of the man handling the nozzle but it further often requires considerable mutilation of a building in order to reach the fire and also incurs the hazard of excess water damage.

The principal objects of my invention are, therefore, to provide a swivelling nozzle that can be admitted to practically any location and whereby a stream of liquid issuing therefrom can be aimed in either a straight direction or at various angles to a hose without movement of the hose and without leakage of fluid from the swivel joint.

In accomplishing these and other objects of my invention I have provided improved details of structure, the preferred forms of which are illustrated in the accompanying drawing, wherein:

Fig. 1 is a perspective view showing a nozzle constructed in accordance with my invention and inserted through an opening formed by removing the base board of a wall, the wall being further broken away to disclose the discharge end of the nozzle.

Fig. 2 is a longitudinal central section through the nozzle illustrating particularly the manner of packing the swivel joint.

Fig. 3 is a similar view in elevation, with portions shown in section, of the nozzle provided with a modified form of tip.

Referring more in detail to the drawing:

40 1 designates a portion of a room including a floor 2, walls 3 and 4 and a base board 5. For the purpose of illustrating the manner of using my invention for extinguishing a fire burning within a wall, the base board of wall 3 is shown removed for admitting a nozzle assembly 7 between laterally spaced laths 8 and 9 of the wall. The nozzle assembly includes a shank 10 having one end threadedly engaging the nipple end 11 of a shut-off valve 12 and having an externally threaded opposite end 13 for engaging a forty-five degree elbow 14 although obviously the elbow could comprise an integral part of the shank. Threadedly engaging or otherwise secured in the end of the elbow opposite the shank is a socket member 15 preferably counterbored to produce

stepped lateral shoulders 16 and 17, for purposes presently described, and terminating in an internally threaded enlarged end 18 of substantially greater diameter than said elbow.

A tubular section 19, cooperating with the socket member to form a union, is provided adjacent one end with an annular flange or thrust ring 20 adapted to seat on the smaller shoulder 16, and a thrust washer 21 slidably mounted on the section for seating contact with the larger shoulder 17, is forced into engagement therewith by a packing nut 22 spaced from the washer by packing material 23.

Attention is directed to the width or thickness of the ring 20 which is less than the width of the space between the stepped shoulders so that, with the thrust washer in seated condition on the large shoulder, the tubular section will not bind in the socket member but can move slightly longitudinally therein.

It should also be noted that the outside diameter of the section and adjacent the thrust ring is such that it snugly seats in the reduced or neck portion of the socket member to further aid in sealing the joint of the union against leakage of fluid.

The end of the tubular section opposite the ring is secured to a second forty-five degree elbow 24 which in turn may be connected by a nipple 25 to a nozzle tip 26.

With a nozzle assembly constructed and attached to a hose as described the tip and tubular section may be rotated through a complete circle or to any position relative to the socket member, but because of the friction of the packing material on the tubular section and by reason of the pressure at which the water is discharged from the nozzle assembly the nozzle tip will remain stationary at any position to which it has been turned.

The packing should be forced by the nut to sealing engagement with the tubular section and socket member but should not be packed sufficiently tight to effect binding and prevent rotation of the section in the socket member.

Since the nozzle tip will remain in the position it is turned it is possible for a fireman to insert the nozzle into a wall as shown in Fig. 1 and to thereafter withdraw his hand from the wall to avoid being burnt by scalding water which frequently happens when a nozzle must be held in an upwardly pointing position.

With my improved nozzle assembly it is possible to more accurately direct water or other extinguishing liquid to a fire thus reducing the

danger of damaging material with water and expediting fire extinguishing operations.

By using suitable adapters the nozzle can be made to fit any shut-off valve thereby eliminating 5 the necessity of supplying independent nozzles for various types and sizes of valves.

In Fig. 3 I have shown the nozzle assembly provided with an adapter or reducing nipple 27 whereby an adjustable nozzle 28 for a garden hose 10 or the like may be connected to the assembly and can be manipulated in exactly the same manner as described for operation of the fire nozzle.

What I claim and desire to secure by Letters Patent is:

- 15 1. A device of the character described including a shank, a forty-five degree elbow on the shank, a nozzle tip, a forty-five degree elbow on the tip, and a swivel union connecting said elbows whereby the tip can be moved from a position parallel to the shank to an angular relation of ninety degrees to the shank.
- 20 2. A device of the character described including a shank, a forty-five degree elbow on the shank, a nozzle tip, a forty-five degree elbow on the tip, a socket member secured to one elbow, a tubular section secured to the other elbow and adapted to seat in said socket member, and means for operably connecting said section and socket member.
- 25 3. In a device of the character described, a shank including a forty-five degree elbow, a nozzle tip including a forty-five degree elbow, a

socket member secured to one elbow and having a seat, a tubular section secured to the other elbow and having a radial flange adapted to engage said seat, and means for urging said flange into engagement with the seat including means for packing the tubular section in said socket member.

4. In a device of the character described, a shank including a forty-five degree elbow, a nozzle tip including a forty-five degree elbow, a socket member secured to one elbow and having progressively stepped annular shoulders, a tubular section secured to the other elbow and having a radial flange adapted to seat on the smaller of said shoulders, a thrust washer slidably mounted on the tubular member and adapted to seat on the larger of said shoulders for locking said flange between the washer and smaller shoulder and reserving a limited amount of freedom of longitudinal movement of the tubular section in the socket member, and means for holding the washer against said larger shoulder.

5. A device of the character described including a shank, a forty-five degree elbow in fixed relation to the shank, a nozzle tip, a forty-five degree elbow in fixed relation to the tip, a socket member secured to one elbow, a straight tubular section secured to the other elbow and adapted to seat in the socket member, and means for swivelly connecting the tubular section and socket member.
